UNITED STATES PATENT OFFICE.

WILLIAM M. BAXTER, OF CHICAGO, ILLINOIS.

CHARCOAL-BURNER.

1,188,880.

Specification of Letters Patent. Patented June 27, 1916.

Application filed March 31, 1913. Serial No. 757,916.

REISSUED

To all whom it may concern:

Be it known that I, WILLIAM M. BAXTER, a citizen of the United States, residing at Chicago, in the county of Cook and State 5 of Illinois, have invented new and useful Improvements in Charcoal-Burners, of which the following is a specification.

My invention relates to improvements in heaters and germ-destroying devices, and 10 more particularly to heaters which have special application to transportable containers employed to carry fruits, vegetables, and the like to distant points.

My present application has special reference to a heater designed to burn charcoal, charcoal products, or their equivalent in specific gravity, for the purpose of maintaining a uniform heat for a long period of time.

20 One of the objects of my invention is the dissemination of a product of charcoal combustion (carbon monoxide gas) within a closed container, as a car body, for the purpose of retarding the ripening process by 25 delaying the action of fermentation in the fruit or vegetable contents of a car.

Another object is to provide a burner that will furnish, without special attention, a predetermined amount of uniform heat 30 for a given length of time.

Another object is to construct the base of the heater, upon which the combustion chamber rests and is a part, so that the downward radiation of the heat from the grate will be 35 prevented, whereby danger of fire to the car is reduced to a minimum.

Another object is to provide means whereby the draft and depth of the fire may be controlled so as to provide a uniform heat 40 that will continue for a predetermined length of time and also provide an outlet for the burnt gases that will vary in direct proportion to the thickness of the fire.

Another object is to provide a construction 45 wherein draft openings are arranged indirectly so that burning embers will not escape from the heater in case the heater is overturned, or otherwise disturbed.

Still another object is to provide means 50 whereby the heater may be suspended from the ceiling of a car, or supported upon the floor of the car.

Of what it consists and its manner of construction and mode of operation, will be 55 fully set out, described and illustrated in the following specifications, when read in

connection with the drawings accompanying the same and forming a part hereof.

Figure 1, is a perspective view of the device with the part cut away showing the fire 60 pot and surroundings; Fig. 2, is a vertical sectional view of a heater, Fig. 3, is a perspective view of fire pot and base, and Fig. 4, is a face view of the adjusting hasp and portions of the heater casing to which it 65 is attached.

Before referring to a detailed description of parts that enter into the particular exemplification of my invention herein presented, it is suggested that following my 70 plan the object is to be attained of heating a car exactly at a proper and uniform temperature for a period of days, comprehending full efficiency and capabilities to meet the requirements of shipments, fruits, vegetables and the like, for the longest distances that are ordinarily required, and this without the requirement of any attention whatever to the heater during the whole of the 75 transportation period.

Like characters of reference denote corresponding parts in each of the drawings.

Referring to the drawings: 2 designates the casing or shell of my heater device, which is constructed of a tubular sheet metal part, 85 preferably formed with corrugations 4, and this tubular part has a top secured to the upper end thereof with a fuel opening which is normally closed by the removable lid or cover 5. Within the upper end of the casing is formed a magazine 8 for the charcoal, 90 which magazine has a conical bottom, through the center of which is an opening controlled by a slide 12, which said slide is provided with a handle 14 that projects 95 through the shell (and is provided with holes 11^a through which a pin 11 is inserted) to control the position of the slide over the opening in the base of the conical portion of the magazine. Secured to the conical bottom of the magazine is a tapering tube 15 formed with an inner member 17 connected to the rim of the opening in the bottom of the magazine and extending downwardly therefrom, as shown; this construction 100 providing an air space between said members forming tube 15 for the purpose of preventing pre-ignition of the fuel in the feed tube 17 before it falls to the fire on the grate. Surrounding the tube 15 is a 110

circular fire box 16 provided with an opening 19 in its top of substantially the size of

the largest part of the tapering tube 15 through which opening 19 projects said tube 15, and by which the draft and gases are controlled. Within the fire-box is a conical 5 shaped grate 18 preferably made of braided or woven wire. Within the fire-box 16 is a sheet metal tube 22 which rests upon the grate 18 and prevents the fuel from coming in contact with the fire-box 16, thus preventing 10 the fire-box from burning out, and also creating a diffusion of heat in the fire-box which prevents the shell 16 from radiating too much heat to the shell 2 at one place but distributing the heat over a large area of the shell. If the tube 22 burns out it can be 15 readily replaced.

Below the fire-box is an ash receiver 24, which is of a conical shape, similar to the 20 grate surface 18 and the fire-box is supported on this ash receiver 24 by means of an extension 26, which projects downwardly from the fire-box casing 16 and is secured to the ash receiver 24, a suitable distance being provided between the grate 18 and ash 25 receiver 24 to allow for the reception of the ash deposit from the grate 18 and also to provide for circulation of air. This downwardly extending portion 26 is provided with a number of draft openings 29 therein, 30 which openings extend down to the surface of the ash receiver as shown, so as to provide an outlet for the ash deposit from under the grate surface 18. This ash receiver 24 is disposed intermediate of the ends 35 of a tubular casing 30, the lower portion of which, below the ash receiver 24, forms a base or support for the entire heater; the distance from the ash receiver 24 to the lower end of casing 30 being sufficient to 40 hold the heater far enough above the floor, so that there is no danger of heat being communicated from the heater to the floor. To further prevent downward radiation of heat there is provided a plate or bottom 25 45 secured in the casing 30 immediately below the ash receiver 24, which has a number of sheets 28 of asbestos or some other heat non-conducting material thereon. The casing 30 below the plate 25 is provided with a 50 number of holes 31 for free circulation of air, and this together with the sheets 28 of heat non-conducting material and the dead air space formed between the plate 25 and the ash receiver 24 effectually prevent downward radiation of heat from the combustion 55 chamber.

The casing 30 extends a suitable distance above the ash receiver 24 and loosely telescopes the lower end of the casing 2, so as 60 to provide an air space between the telescopic walls thereof for admission of air to the lower part of the combustion chamber. For securing the casing 30 and the casing 2 together, there are a number of hasps 34 which 65 are secured around the lower portion of the

casing 2, these hasps each having a number of slots 34 and 35 through which the buttons 36 on the casing 30 may be passed for securing the two casings 30 and 2 together. As is apparent, the hasps allow adjustment 70 whereby the casing 2 may be inserted and secured at different distances within the casing 30 and in order that there may be free communication of air to the bottom of the combustion chamber, in all positions of 75 adjustment there are provided a number of openings 33 in the casing 2 at the lower end thereof.

In practice, it is often desirable to suspend the heater from the ceiling of the car 80 and for this purpose casing 2 is provided with hooks 42 at the upper end whereby the entire heater may be suspended.

The mode of operating my device is substantially as follows: The pin 11 is removed 85 and the slide 12 is forced down and closes the opening in the base of the magazine. Then the button 36 is turned and the hasps 32 are unlocked from the buttons and the entire casing with the magazine is removed 90 from off the fire pot. The fire is started on the grate 18 with a small quantity of charcoal. After it comes to a glow the magazine is filled with the fuel and then the casing is replaced and locked by the buttons 36. 95 The slide 12 is pulled out by means of the handle 14 to full open position and the pin 11 inserted to retain it in this position. As soon as the slide is removed the fuel in the magazine 8 passes down within the fuel 100 tube 17 onto the fire on the grate, then as the fuel is consumed it is supplied from the magazine by gravity.

Assuming that the heater parts are in the position indicated in Fig. 2, fuel will 105 be deposited from the magazine 8 onto the grate surface 18 until the fuel in the combustion chamber reaches the lower end of the fuel tube 17. As the fuel is consumed and settles on the grate surface 18, a fresh 110 supply will be automatically fed from spout 17.

If it is desired to decrease the depth of fuel on the grate surface 18, the buttons 36 are released so as to allow hasps 32 to be 115 withdrawn from engagement therewith, and the entire casing 2 is inserted still farther within casing 30 until the upper openings 34 in the hasps 32 are in position to engage with the buttons 36. These parts are 120 then secured together by means of the buttons 36.

The insertion of the casing 2 within the casing 30 projects the tapering tube 15 and fuel tube 17 farther within the opening 19 of the combustion chamber thereby decreasing the draft passage way through the opening 19 and decreasing the distance between the lower end of the tube 17 and the grate 125 surface 18. It will require a less quantity 130

of fuel on the grate surface 18 to reach the bottom of the fuel tube 15 and a thinner layer of fuel will be maintained on the surface 18. The diminishing of the draft opening 19 above mentioned will cause the fuel to burn more slowly and the heat radiated from the combustion chamber will be correspondingly lessened.

It will be observed that with the method 10 of fastening the heater casings together by means of the hasps 32, there is little danger of the heater coming apart and furthermore, the construction of the combustion chamber is such and the construction of the draft 15 passage to the bottom of the combustion chamber so indirect, that there is practically no danger of any burning embers escaping from the heater if overturned.

Having now described my invention what 20 I claim is:

1. In a heater, in combination, a combustion chamber having a grated bottom, double side walls spaced from each other, and a top closure wall overlying the upper 25 edge of the double side walls and extending inwardly toward the vertical center of the combustion chamber, a support for the combustion chamber, a fuel magazine provided with an outlet for communication with the 30 combustion chamber, a casing connecting the fuel magazine with the support for the combustion chamber spaced from the latter and provided with inlets to permit air to enter at points below the combustion chamber 35 and for circulation through the space between said combustion chamber and the casing and provided with outlets to permit the escape of gases from the inclosure.

2. In a heater, in combination, a combustion chamber having a grated bottom, double side walls spaced from each other, and a top closure wall overlying the upper 40 edge of the double side walls and extending inwardly toward the vertical center of the combustion chamber, a support for the combustion chamber, a fuel magazine provided with an outlet for communication with the combustion chamber, a casing connecting the fuel magazine with the support for the 45 combustion chamber, spaced from the latter and provided with air inlets for admission of air within the inclosure and with outlets for the escape of gases therefrom.

3. In a heater, in combination, a combustion chamber, a base spaced from the combustion chamber and suitably supporting the same, and provided with upwardly extending, circumferential, walled portions, a magazine provided with an outlet chute, a 50 casing depending from the fuel magazine, surrounding the combustion chamber and suitably spaced therefrom, members suitably correlated to facilitate vertical adjustment relatively of the base and the casing 55 to control air circulation through the com-

bustion chamber, inlets for the admission of air to points within the inclosure, and outlets for the escape of gases therefrom.

4. In a charcoal heater, in combination, a fire pot and a magazine spaced apart, the former below the latter, the fire pot having a grated bottom portion, closed side walls and an inwardly extending flanged portion partially closing the top thereof, but open sufficiently, approximating its central portion, to permit discharge of fuel thereinto, the circulation of air therethrough and the escape of gases therefrom, the magazine provided with a discharge spout communicating for discharge through the opening 75 in the top portion of the fire pot and means for varying the spaced relation between the grate of the fire pot and the discharge outlet opening from the magazine whereby the escape of the products of combustion from 80 the combustion chamber is retarded and carbon monoxide is generated in abundance, and a casing connecting the magazine with the fire pot and provided with air inlet ways for communication of air to the grate, and 85 with discharge openings for permitting the escape of gases generated in the heater to points without.

5. In a heater, in combination, a base portion, a fire pot spaced from said base portion, adapted to burn charcoal and provided with a grate and having a top closure portion provided with an inlet opening, a magazine communicating for discharge through the opening into the fire pot, and 90 disposed with relation to said opening and with the grate of said fire pot in a manner to retard normal combustion for the purpose of producing carbon monoxide gas, a casing provided with outlet openings adjacent the 95 top of the fire pot, said casing being spaced from the fire pot and connecting the magazine and the base portion and provided with inlet openings at points adjacent the space below the fire pot and communicating therewith and with the space between the fire pot 100 and the casing for communication both with the space above and below said fire pot, whereby air is supplied to the fire pot and also to the space between the fire pot and 105 the casing to cool the outer wall of the former, and also communicates with the space above the fire pot to be commingled with the carbon monoxide gas.

6. In a device of the class described, the 110 combination of a combustion chamber provided with a restricted draft opening in the top and with a reticular bottom, a fuel magazine communicating through the opening in the fire pot with the interior of the 115 combustion chamber in a manner to restrict the escape of gases therefrom and the circulation of air therethrough for the purpose of retarding combustion therein to produce carbon monoxide gas, a wall spaced from the 120

combustion chamber to form a space below the same, communicating through the said reticular bottom with said combustion chamber, a casing provided with air inlet openings adjacent the space below the fire pot and with gas outlet openings adjacent the top thereof consisting of separable parts inclosing and spaced from the combustion chamber and forming a draft passageway

therebetween, said passageway communicating with the draft space below the combustion chamber. 10

In witness whereof I affix my signature in presence of two witnesses.

WILLIAM M. BAXTER.
